UNITED STATES PATENT OFFICE

DANIEL G. BANKER, OF DANSVILLE, NEW YORK, ASSIGNOR OF THREE-EIGHTHS TO MERTON E. WESTCOTT AND ONE-FOURTH TO FRANK McCONNELL, BOTH OF CORNING, NEW YORK.

DESIGN FOR A SIGNAL BOX FOR MOTOR VEHICLES.

Application filed December 1, 1921. Serial No. 519,302. Term of patent 3½ years.

To all whom it may concern:

Be it known that I, DANIEL G. BANKER, a citizen of the United States, residing at Dansville, in the county of Livingston and State of New York, have invented a new, original, and ornamental Design for Signal Boxes for Motor Vehicles, of which the following is a specification, reference being had to the accompanying drawing, forming part thereof, in which—

Figure 1 is a rear elevation of a signal box showing my new design, Figure 2 is a front elevation thereof, and Figure 3 is a top plan view.

I claim:

The ornamental design for a signal box for motor vehicles, as shown.
